Attorney

UNITED STATES PATENT OFFICE.

JONATHAN WENGERD, OF DALTON, OHIO.

LOCK.

1,321,345.

Specification of Letters Patent. Patented Nov. 11, 1919.

Application filed March 24, 1919. Serial No. 284,543.

To all whom it may concern:

Be it known that I, JONATHAN WENGERD, citizen of the United States, residing at Dalton, in the county of Wayne and State of Ohio, have invented certain new and useful Improvements in Locks, of which the following is a specification, reference being had to the accompanying drawings.

This invention relates to certain improvements in locks, and has relation more particularly to a device of this general character of a permutation type, and wherein rotary tumblers are employed, and it is an object of the invention to provide a lock of this class having novel and improved means whereby the requisite endwise movement is imparted to the bolt.

It is also an object of the invention to provide a novel and improved lock of this character whereby the bolt is effectually held against retrograde movement when extended, together with means movable in a direction substantially at right angles to the bolt for releasing the same and permitting retraction of the bolt upon rotation of the last named means.

The invention consists in the details of construction and in the combination and arrangement of the several parts of my improved lock whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation of a lock constructed in accordance with an embodiment of my invention, and with the bolt extended;

Fig. 2 is a sectional view taken substantially on the line 2—2 of Fig. 1;

Fig. 3 is a view in elevation of one of the tumblers or disks as herein embodied;

Fig. 4 is a view in elevation of the inner end of the spindle as herein employed;

Fig. 5 is a view in elevation of the inner side of the bolt; and

Fig. 6 is a view in elevation of the inner end of the second rotary tumbler comprised herein.

As disclosed in the accompanying draw-

ings, C denotes a casing of requisite dimensions and configurations, and which is provided in a side or edge wall with an opening 1 through which the bolt B is movable. 60

A side face of the casing C is provided with an inwardly directed annular flange 2, and said side face of the casing at the axial center of the chamber defined by said flange 2 is provided with an inwardly directed 65 finger or pin 3.

4 denotes a tumbler or disk which has its peripheral portion in contact with the inner or free edges of the flange 2, and said disk or tumbler 4 is provided with a radially disposed slot 5 enlarged adjacent its outer end portion as indicated at 6.

The inner end portion 7 of the bolt B is transversely enlarged and said portion 7 is provided with a longitudinally directed slot 75 8 similar in form to the slot 5 hereinbefore referred to and for a purpose to be herein-after explained.

The portion 7 of the bolt B overlies the tumbler or disk 4 and the face of said portion 7 opposed to the tumbler or disk 4 is provided with an annularly directed groove or channel 9 substantially concentric to the inner end portion of the slot 8, and a portion 10 of said channel 9 to one side of the 85 slot 8 is enlarged toward the inner end of the slot 8 and said enlargement comprises substantially a segment of ninety degrees, so that a straight shoulder 11 is arranged at the inner end of the slot 8 and substantially 90 at right angles to the longitudinal axis of said slot. The groove or channel 9 is not continuous, but has its end portions terminating in close proximity one to the other but slightly separated, so that a second shoulder 12 is also provided.

Interposed between the portions 7 of the bolt B and the second or front face of the casing C is a second rotary tumbler 14 provided at its axial center with an opening 15, 100 and which opening 15 is adapted to register with the inner end portions of the slots 5 and 8. The outer end portion of the tumbler 14 is provided with an annular extension 16 concentric to the opening 15, and which snugly fits within an opening 17 produced in the second or front face of the casing C. 105

In the present embodiment of my invention the opening 15 comprises the bore of a bushing or sleeve 18 disposed axially through the tumbler 14 and suitably engaged therewith so that said bushing or

sleeve 18 is substantially an integral part of the tumbler 14. The bushing 18 has its outer end portion extended beyond the front face of the casing C and terminating in a 5 disk 19, and which disk 19 has its peripheral portion provided with the identified graduations 20 coacting with an annular series of identified graduations 21 produced on the outer surface of the front face of the casing 10 C, and which is particularly illustrated in Fig. 1. Disposed through the opening 15 of the tumbler 4 and the inner end portions of the openings 5 and 8 is a spindle 22. The inner end of the spindle 22 is provided with 15 a socket 23 to receive the finger or pin 3 and the opposite end portion of the spindle terminates outwardly of the disk 19, and suitably secured to the extended portion of the spindle 22 is an operating member 24 20 whereby endwise or rotary movement may be imparted to the spindle 22. The inner end portion of the spindle 22 is provided with a laterally directed wing 25 of a configuration conforming to the inner portions 25 of the slots 5 and 8 and the enlarged portions 6 and 6' thereof, so that when said slots 5 and 8 are in register, endwise movement may be imparted to the spindle 22.

The inner face of the tumbler 14 in radial 30 alignment with the opening 15 thereof is provided with a pocket or recess 26 of a depth to completely receive or house the spherical member 27. The enlarged portion 6' of the slot 8 is also of a size to readily receive the member 27 when the recess or 35 pocket 26 is brought into register therewith, and in order to assure the seating of the member 27 within said enlarged portion of the slot 8, I interpose between the inner end 40 of the recess of pocket 26 and the member 27 an expansible member 28 herein disclosed as a coil spring. It is also to be noted in Fig. 2 that the bolt B or more particularly the portion 7 thereof is of such thickness 45 that the member 7 is completely housed or received within the portion 6' of the slot 8. When the member 27 is within the portion 6' of said slot 8 it will be impossible to retract the bolt B.

50 The inner face of the wing 25 at its outer end is provided with an upstanding finger or tongue 29 which is adapted to ride within the groove or channel 9 hereinbefore referred to, to extend or retract the bolt B as 55 will be hereinafter set forth.

As illustrated in Fig. 2, the bolt B is shown extended with the tumblers 4 and 14 in proper adjustment relative to the slot 8 of the bolt B, and to retract the bolt B 60 it is only necessary to pull the spindle 22 outwardly, which will result in the member 27 being received within the recess or pocket 26 and the finger or tongue 29 extending within the groove or channel 9. 65 The tumbler 14 is then rotated to carry

the member 27 away from the slot 8 and the spindle 22 moved longitudinally to the limit of its inward movement. With the spindle in this position rotation is imparted thereto toward the right, which 70 brings the finger or tongue into contact with the shoulder 11 so that inward movement will be imparted to the bolt B. Rotary movement may then be imparted to the tumbler 14 through the medium of the disk 75 19 so that the moving of the bolt B into extended position may be made more difficult.

When it is desired to extend the bolt B the tumbler 14 is adjusted in accordance 80 with the desired combination and as determined by the identified graduations 20 and 21 until the pocket or recess 26 is properly positioned. The spindle 22 is then rotated with the operating member or head 24 serving as an index acting in conjunction with the identified graduations 21 to properly position the wing 25 and also the slot 5 of the tumbler or disk 4. This movement of the spindle 22 results in the forward movement 90 of the bolt B so that at the proper moment the member 27 will be received within the enlarged portion 6' of the slot of the bolt B whereby said bolt B is effectively maintained against retraction. The spindle 22 95 may be further rotated so that the same will not be properly set to effect a retraction of the bolt. It will also be self evident that the contact of the finger or tongue 29 with the forward wall of the groove or channel 100 9 will result in the forward or extended movement of the bolt B.

From the foregoing description, it is thought to be obvious that a lock constructed in accordance with my invention is particularly well adapted for use by reason of the convenience and facility with which it may be assembled and operated, and it will also be obvious that my invention is susceptible of some change and modification without departing from the principles and spirit thereof, and for this reason I do not wish to be understood as limiting myself to the precise arrangement and formation of the several parts herein shown in carrying out my 110 invention in practice except as hereinafter claimed.

I claim:

1. A lock of the class described including a casing, a sliding bolt movable relative 120 to said casing and having a longitudinally directed slot in its inner end portion, rotary tumblers arranged at opposite sides of the inner end portion of the bolt, one of said tumblers having a slot adapted to register 125 with the slot of the bolt, the second tumbler having an opening therethrough adapted to register with the inner edge portions of the slot of the bolt and the slot of the first named tumbler, the inner face of said sec- 130

ond tumbler being provided with a pocket, a member adapted to be housed within the pocket of the second tumbler and adapted to seat within the slot of the bolt when the 5 pocket of said tumbler is in register with the slot of the bolt, a spindle disposed through the inner end portions of the slots in the first named tumbler and the bolt and through the opening in the second tumbler, 10 said spindle being capable of both rotary movement and endwise movement, the inner end portion of the spindle being provided with a laterally disposed wing adapted to extend through the slots of the first 15 named tumbler and the slot in the bolt when said slots are in register and outward endwise movement is imparted to the spindle, so that the wing will force the member within the slot of the bolt into the pocket 20 of the second tumbler, and coacting means carried by the wing and bolt for imparting endwise movement to the bolt upon rotation of the spindle when in extended position.

2. A lock of the class described including 25 a casing, a sliding bolt movable relative to said casing and having a slot, rotary tumblers arranged at opposite sides of the bolt, one of said tumblers having a slot adapted to register with the slot of the bolt, the second 30 tumbler having an opening therethrough adapted to register with the inner edge portions of the slot of the bolt and the slot of the first named tumbler, the inner face of said second tumbler being provided with a 35 pocket, a member adapted to be housed within the pocket of the second tumbler and adapted to seat within the slot of the bolt when the pocket of said tumbler is in register with the slot of the bolt, a spindle disposed 40 through the inner end portions of the slots in the first named tumbler and the bolt and through the opening in the second tumbler, said spindle being capable of both rotary movement and endwise movement and 45 the inner end portion of the spindle being provided with a laterally disposed wing adapted to extend through the slots of the first named tumbler and the slot in the bolt when said slots are in register and outward endwise movement is imparted to the spindle, so that the wing will force the member within the slot of the bolt into the pocket of the second tumbler, and coacting means carried by the 50 wing and bolt for imparting endwise movement to the bolt upon rotation of the spindle when in extended position, the inner face of the casing being provided with an outwardly directed finger, the inner end of the spindle being provided with a socket to receive said finger, said inner face of the casing being also provided with an inwardly directed annular flange concentric to the finger, the first named tumbler contacting with the inner edge of said flange, the wing of the 55 spindle being arranged within the chamber defined by said flange and within the slot of the first named tumbler when the spindle is at the limit of its inward movement.

4. A lock of the class described including 60 a casing, a sliding bolt movable relative to said casing and having a longitudinally directed slot in its inner end portion, rotary tumblers arranged at opposite sides of the inner end portion of the bolt, one of said tumblers having a slot adapted to register with the slot of the bolt, the second tumbler having an opening therethrough adapted to register with the inner edge portions of the slot of the bolt and the slot of the first 65 named tumbler, the inner face of said second tumbler being provided with a pocket, a member adapted to be housed within the pocket of the second named tumbler and adapted to seat within the slot of the bolt when the pocket of said tumbler is in register with the slot of the bolt.

3. A lock of the class described including 70 a casing, a sliding bolt movable relative to said casing and having a longitudinally di- 75 rected slot in its inner end portion, rotary tumblers arranged at opposite sides of the inner end portion of the bolt, one of said tumblers having a slot adapted to register with the slot of the bolt, the second tumbler having an opening therethrough adapted to register with the inner edge portions of the slot of the bolt and the slot of the first named tumbler, the inner face of said second tumbler being provided with a pocket, 75 a member adapted to be housed within the pocket of the second tumbler and adapted to seat within the slot of the bolt when the pocket of said tumbler is in register with the slot of the bolt, a spindle disposed 80 through the inner end portions of the slots in the first named tumbler and the bolt and through the opening in the second tumbler, said spindle being capable of both rotary movement and endwise movement, the inner 85 end portions of the spindle being provided with a laterally disposed wing adapted to extend through the slots of the first named tumbler and the slot in the bolt when said slots are in register and outward endwise movement is imparted to the spindle, so that the wing will force the member within the slot of the bolt into the pocket of the second tumbler, and coacting means carried by the 90 wing and bolt for imparting endwise movement to the bolt upon rotation of the spindle when in extended position, the inner face of the casing being provided with an outwardly directed finger, the inner end of the spindle being provided with a socket to receive said finger, said inner face of the casing being also provided with an inwardly directed annular flange concentric to the finger, the first named tumbler contacting with the inner edge of said flange, the wing of the 95 spindle being arranged within the chamber defined by said flange and within the slot of the first named tumbler when the spindle is at the limit of its inward movement.

4. A lock of the class described including 100 a casing, a sliding bolt movable relative to said casing and having a longitudinally directed slot in its inner end portion, rotary tumblers arranged at opposite sides of the inner end portion of the bolt, one of said tumblers having a slot adapted to register with the slot of the bolt, the second tumbler having an opening therethrough adapted to register with the inner edge portions of the slot of the bolt and the slot of the first 105 named tumbler, the inner face of said second tumbler being provided with a pocket, a member adapted to be housed within the pocket of the second named tumbler and adapted to seat within the slot of the bolt when the pocket of said tumbler is in register with the slot of the bolt, a spindle disposed 110 through the inner end portions of the slots in the first named tumbler and the bolt and through the opening in the second tumbler, said spindle being capable of both rotary movement and endwise movement and the inner end portion of the spindle being provided with a laterally disposed wing adapted to extend through the slots of the first named tumbler and the slot in the bolt when said slots are in register and outward endwise movement is imparted to the spindle, so that the wing will force the member within the slot of the bolt into the pocket of the second tumbler, and coacting means carried by the 115 wing and bolt for imparting endwise movement to the bolt upon rotation of the spindle when in extended position, the inner face of the casing being provided with an outwardly directed finger, the inner end of the spindle being provided with a socket to receive said finger, said inner face of the casing being also provided with an inwardly directed annular flange concentric to the finger, the first named tumbler contacting with the inner edge of said flange, the wing of the 120 spindle being arranged within the chamber defined by said flange and within the slot of the first named tumbler when the spindle is at the limit of its inward movement.

5. A lock of the class described including 125 a casing, a sliding bolt movable relative to said casing and having a longitudinally directed slot in its inner end portion, rotary tumblers arranged at opposite sides of the inner end portion of the bolt, one of said tumblers having a slot adapted to register with the slot of the bolt, the second tumbler having an opening therethrough adapted to register with the inner edge portions of the slot of the bolt and the slot of the first named tumbler, the inner face of said second tumbler being provided with a pocket, a member adapted to be housed within the pocket of the second named tumbler and adapted to seat within the slot of the bolt when the pocket of said tumbler is in register with the slot of the bolt, a spindle disposed 130 through the inner end portions of the slots in the first named tumbler and the bolt and through the opening in the second tumbler.

bler, said spindle being capable of both rotary movement and endwise movement, the inner end portions of the spindle being provided with a laterally disposed wing adapted to extend through the slots of the first named tumbler and the slot in the bolt when said slots are in register and outward endwise movement is imparted to the spindle, so that the wing will force the member within the slot of the bolt into the pocket of the second tumbler, the inner face of the bolt being provided with an annularly directed groove substantially concentric to the inner end of the slot of said bolt, an end portion

of the groove being enlarged to afford a shoulder substantially radial to the inner end of the slot of the bolt, the wing of the spindle being provided with a tongue adapted to travel in said groove of the bolt when the spindle is at the limit of its inward movement.

In testimony whereof I hereunto affix my signature in the presence of two witnesses.

JONATHAN WENGERD.
